UNITED STATES PATENT OFFICE.

JOHN FREDERICK HYDE, OF SAULT STE. MARIE, ONTARIO, CANADA.

CANOE OR BOAT CONSTRUCTION.

Application filed July 26, 1928. Serial No. 295,537.

My invention relates to improvements in canoe or boat constructions, and the object of the invention is to devise a canoe or boat which can be easily and quickly sectionally divided so as to be rendered compact for transportation, and yet the sections of which when connected provide a rigid and water tight structure, and it consists essentially of the arrangement and construction of parts 10 as hereinafter more particularly explained.

Fig. 1 is a plan view of a canoe constructed in accordance with my invention.

Fig. 2 is a side elevation of my canoe.

Fig. 3 is a side elevation of the divided 15 sections of the canoe in nested position.

Fig. 4 is an enlarged plan sectional detail showing the fastening means between the sections.

Fig. 5 is a plan sectional detail looking 20 edgewise upon one of the clip fasteners.

Fig. 6 is a side elevation of the parts shown in Fig. 5.

Fig. 7 is a fragmentary detail showing the 25 separable connection between the gunwale portions of each section.

Fig. 8 is a perspective detail of the operating lever employed in assembling and disassembling the device.

Fig. 9 is an inverted plan section showing 30 the means for connecting the keel sections together.

Fig. 10 is a sectional view through Fig. 9.

In the drawing like characters of reference indicate corresponding parts in each 35 figure.

1, 2, 3 and 4 are the sections of a canoe each provided with a gunwale portion 5. 6 and 7 are hinge members countersunk in the abutting ends of the gunwale portions 40 and provided with a removable hinge pin 8. 9 is an internal rib member extending around the transverse edge of each section between the gunwale portion on one side of the canoe or boat to the gunwale portion on the opposite side.

When the sections are assembled together as indicated in Figure 1 the rib portions 9 of the abutting ends of the sections bear one against the other and between which is inserted a packing strip of wick material or any other suitable form of packing which may be cemented or otherwise suitably secured to one of the ribs 9. The ribs 9 are preferably formed of three ply thickness, 55 but may be of any suitable structure desired.

10 are cam members secured to the inner

face of each rib 9, a cam member 10 being on each side of the double rib of two abutting sections as clearly indicated in Figure 4. 11 is a bearing strap secured to the upper edge 60 of one of the ribs 9. 12 is a clip which is in the form of a round bar extending transversely of the abutting ribs 9, the ends of the bar being bent inward in semi-circular form so that the extremities thereof may be 65 brought into bearing contact with the cams 10. 13 is an operating lever provided with a head 13^x carrying a double fork, the members of which are designated by the numerals 14 and 15.

When it is desired to unlock or lock the sections together the lever is placed in the dotted position indicated in Figure 5 and the lever swung transversely of the canoe or boat so as to carry the extremities of the 75 clip 12 into or out of engagement with the cams 10. As the clip is forced downward into locking engagement it rides up the inclined surfaces of the cams 10 forcing the opposing ribs 9 into tight contact and thereby securely and rigidly locking them together so as to form a tight joint.

16 is a plate countersunk in the keel edge 18 and provided with an offset portion 16^x having a transverse slot 16^y which overhangs the division between the keel sections, and 17 is a plate similarly secured to the end of the keel section next adjacent and provided with a downturned tongue 17^x which is hooked into the slot 16^y to connect 80 the ends of the keel sections together.

From this description it will be seen that I have devised a very simple construction in which the sections of a canoe or boat when separated apart may be nested one 95 inside the other as illustrated in Figure 3, so that they will occupy a very small space and thereby enable their transshipment in an aeroplane or other situation where the space available is very limited, and yet at the 100 same time provide a structure when assembled which will be absolutely rigid and water tight.

What I claim as my invention is:—

1. In a canoe or boat divided transversely 105 into a plurality of sections, a rib extending around each transverse edge of each section and adapted to bear one against the other when the sections are in an abutting position, and a pivoted clip adapted to bear 110 against each outer side of each pair of ribs to force them into contact.

2. In a canoe or boat divided transversely into a plurality of sections, a rib extending around each transverse edge of each section and adapted to bear one against the other when the sections are in an abutting position, a clip adapted to bear against each outer side of each pair of ribs to force them into contact, and comprising a bearing member carried upon the edge of one rib, a rocking bar member journaled in such bearing member and having inturned ends adapted to bear against the outer surfaces of the ribs when the clip is swung downward. 25
5. In a canoe or boat divided transversely into a plurality of sections, a rib extending around each transverse edge of each section and adapted to bear one against the other when the sections are in an abutting position, a clip adapted to bear against each outer side of each pair of ribs to force them into contact, and comprising a bearing member carried upon the edge of one rib, a rocking bar member journaled in such bearing member and having inturned ends adapted to bear against the outer surfaces of the ribs when the clip is swung downward. 30
10. In a canoe or boat divided transversely into a plurality of sections, a rib extending around each transverse edge of each section and adapted to bear one against the other when the sections are in an abutting position, a clip adapted to bear against each outer side of each pair of ribs to force them into contact, and comprising a bearing member carried upon the edge of one rib, a rocking bar member journaled in such bearing member and having inturned ends adapted to bear against the outer surfaces of the ribs when the clip is swung downward. 35
15. In a canoe or boat divided transversely into a plurality of sections, a rib extending around each transverse edge of each section and adapted to bear one against the other when the sections are in an abutting position, a clip adapted to bear against each outer side of each pair of ribs to force them into contact, and comprising a bearing member carried upon the edge of one rib, a rocking bar member journaled in such bearing member and having inturned ends adapted to bear against the outer surfaces of the ribs when the clip is swung downward. 40
20. In a canoe or boat divided transversely into a plurality of sections, a rib extending around each transverse edge of each section and adapted to bear one against the other when the sections are in an abutting position, a clip adapted to bear against each outer side of each pair of ribs to force them into contact, and comprising a bearing member carried upon the edge of one rib, a rocking bar member journaled in such bearing member and having inturned ends adapted to bear against the outer surfaces of the ribs when the clip is swung downward. 45

to bear against the outer surfaces of the ribs 25 when the clip is swung downward, and a cam plate having inclined surfaces with which the clip extremities are brought into direct contact as they are swung downward at each side of the opposing ribs. 30

4. In a canoe or boat divided transversely into a plurality of sections, a rib extending around each transverse edge of each section and adapted to bear one against the other when the sections are in an abutting position, clips adapted to bear against each outer side of each pair of ribs to force them into contact, and means for connecting the keel portions of each section together end to end consisting of a plate secured to the bottom edge of one keel portion and provided with a downwardly offset slotted end overlapping the line of division between the sections, and a plate secured to the adjacent keel portion and having a down-turned end adapted to pass through the slot of the aforesaid offset portion. 40

JOHN FREDERICK HYDE.
